UNITED STATES PATENT OFFICE

2,440,251

VENDING MACHINE

Joseph M. Devens, Springfield, Mass.

Application June 21, 1944, Serial No. 541,311

3 Claims. (Cl. 312—48)

1

This invention relates to improvements in apparatus for vending or dispensing articles of various kinds.

The principal objects of the invention are directed to the provision of a novel construction and arrangement of parts forming an apparatus for dispensing or vending successive articles.

The apparatus of the invention is characterized by means for storing a plurality of articles to be dispensed in combination with means for receiving successive articles or objects that is arranged and adapted to deliver them one after another.

The novel features of the invention are for purposes of disclosure directed to apparatus for vending bottles such as may contain liquid refreshment but it will be understood that apparatus embodying the novel features of the invention may be adapted for other objects or goods.

Various objects and advantages of the invention will be hereinafter observed in connection with the accompanying description of the invention in the form at present preferred.

In the drawings:

Fig. 1 is a small scale front elevational view of a vending machine embodying the novel features of the invention;

Fig. 2 is a sectional plan view on the line 2—2 of Fig. 1;

Fig. 3 is a sectional plan view on the line 3—3 of Fig. 1;

Fig. 4 is a perspective view of one of the storage shelves of the apparatus; and

Fig. 5 is a large scale partial elevational and sectional elevational view on the line 5—5 of Fig. 3.

Referring now to the drawings more in detail, the invention will be fully described.

The apparatus of the invention may include a cabinet or casing 2 having joined together side, rear, upper and lower walls 4, 6, 8 and 10.

Any or all of the walls may be insulated as may be desired. A front cover or door 12, which if desired may be insulated is arranged for ready and easy removal and securement to the casing.

The lower portion of the casing may contain cooling apparatus and there may be cooling elements connected thereto disposed in the upper portion. Such, however, forms no part of the present invention and is not shown.

A lower floor or wall 14 extends between the side and rear walls of the casing and an upper structure 16 extends between said walls. Such upper structure may include transverse mem-

2

bers 18 secured to the walls and a plate 20 carried thereby for supporting operating mechanism.

Vertically disposed rails 22 have their upper ends secured to the upper structure 16 in any suitable manner and their lower ends are fixed to brackets 24 carried by floor 14.

A plurality of vertically spaced shelf members 26 are disposed on either side of the casing to provide bottle storage means. These members 26 have outer ends movably connected to the inner sides of the side walls 4. This may be accomplished in one way by downwardly extending lips 28 that are received in socket members 30 which are secured to the walls 4. The lips and sockets form hinge means to permit swinging movements of the shelf members up and down between upper and lower positions.

Rods 32 at the inner ends of the shelf members 26 are slidable in slots 34 of the members 22 to limit upward movements of said members 26. The said rods 32 rest in the bottoms of said slots when the shelves are in their lower position to support the same.

Members 36 which may be called doors are hinged to the inner free ends of the shelf members on the rods 32 for swinging movements and have pins or rods 38 in their lower edges for reception in notches 40 of the members 22.

The parts are arranged so that with the pins 38 disposed in the notches 40 and the rods 32 disposed at the bottoms of the slots 34 the shelves are inclined downwardly from their outer ends. Springs 44 have opposite ends secured to members 46 of the shelves and the members 22 which tend to move the shelves upwardly.

Articles 42 such as bottles are placed on the shelves. The innermost bottle of a lower shelf rolls up against the door 36 of that shelf next above which prevents rolling of the group of bottles from said lower shelf.

The springs 44 are constructed and arranged to move the shelves upwardly when all of the bottles on the shelf have been removed therefrom. That is, while the bottles on an upper shelf are removed one by one said upper shelf remains in lower position until the last bottle has been removed therefrom. As the last bottle leaves the shelf the spring means moves the shelf upwardly thereby releasing its door 36 so that it may swing outwardly and release the bottles on the shelf next below.

A pair of spiral members 50 are provided. These may have central arbors 52 which have their lower ends journaled in suitable anti-fric-

tion bearing constructions 54 while their upper ends are journalled in the upper construction 16.

Members 56 are spirally arranged on the arbors 52. These receive therebetween the bottles from the shelves for supporting said bottles.

According to the form of the invention shown, the spiral members which may be referred to as transporters are rotated simultaneously and in the same directions through one-half of a circle or one hundred eighty degrees. This may be accomplished by pinions 60 fixed to the upper ends of the arbors 52 which are in mesh with a gear 62 journalled for rotation at 64.

In each cycle of operation of the apparatus the arbors and thereby the transporters may be moved simultaneously by any suitable means. In one way a lever 66 that is swingable on 64 is connected to a movable member 68 of a solenoid 70 which has an ear 72 pivoted to a stud 74. When the solenoid is energized the lever 66 is moved clockwise and a pawl 76 pivoted thereto engages the teeth 78 of a ratchet 80 fixed to gear 62 so as to move said gear. When the solenoid is de-energized a spring 82 returns the member 68 and lever 66 to initial position against an upper stop 84. A lower stop 85 limits movement of lever 66 as it swings downwardly.

Any other means may be employed for operating the transporters 50.

There may be a coin receiving mechanism which on receiving a coin is adapted to bring about energizing of the solenoid or other operating means but the same is not a part of this invention and is not illustrated.

For the purpose of describing the operation of the mechanism it may be assumed that the operating mechanism shown, or some other suitable mechanism, is adapted to rotate the transporters in each cycle of operation through one hundred and eighty degrees.

The bottles from the uppermost filled shelves, at opposite sides of the transporters, move one by one onto opposite sides of the convolutions of the spiral members at each cycle of operation of the apparatus, said bottles being supported at opposite ends by the said spiral members.

In each cycle of operation each bottle on opposite sides of the transporter is moved downwardly one half the pitch of the spiral and the lowermost bottles are discharged alternately at opposite sides of the transporters and at the bottom thereof so they may be withdrawn through an opening 3 in the cover or door of the casing.

When the last bottle of an upper shelf leaves the said shelf it is relieved of the weight of the bottle so that the spring means 44 of the shelf moves the shelf upwardly thereby to withdraw the pin 39 of the door from the notch 40. In this way the door is free to swing and releases the bottles on the shelf next below so that they may move one by one onto the convolutions of the transporter as the convolutions are presented for receiving bottles.

Thus bottles are delivered successively from the shelves at opposite sides of the transporters as long as there are bottles on the shelves.

Bottles may vary in length and to accommodate them guides 80 are provided on the rear sides of the shelves that have slots 82 for screws 84. The guides may be moved back and forth to engage the neck ends of bottles while other guides such as ribs 86 on the door 12 engage the bottoms of the bottles. These guides 86 may be formed on the door 12 or they may be parts secured thereto, all as may be desired.

Other guides 90 extend upwardly from a bracket 92 for engaging the neck ends of bottles in the transporters. The bracket 92 is provided with slots 94 which receive bolts or screws 96 in engagement with member 14 whereby the guides may be moved in and out to accommodate bottles of different lengths. The upper end of guide 90 may be secured to the structure 16 and extend upwardly past the uppermost shelf.

The shelves are easily and readily removable for purposes of cleaning and the like and are readily supplied with bottles when in place.

Means to prevent rotation of the transporter elements may be provided and may include a lock block 100 adapted to engage the teeth of gear 80. This is carried by the movable member 102 of a solenoid 104 and a spring 106 urges the lock towards the gear 80. Solenoid 104 may be connected in series with solenoid 70 so that they may be simultaneously energized whereby the gear 80 is unlocked for actuation by solenoid 70. Other suitable locking means may be employed.

The apparatus is of such a nature as to be easily constructed and is efficient in operation and by reason of the novel construction a large number of bottles may be stored in a minimum of space.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. Apparatus for dispensing bottles and the like comprising in combination, a casing having side walls, transporters between the said side walls rotatable on vertical axes and having spirally arranged members for receiving and lowering bottles, vertically spaced shelves on opposite sides of and inclined downwardly toward said transporters hingedly connected at outer ends to said side walls whereby their inner ends may swing from lower to upper positions, and means on the inner ends of said shelves adapted to hold bottles on a shelf below against movement therefrom by the weight of bottles on the upper shelf.

2. Apparatus for dispensing bottles and the like comprising in combination, a casing having side walls, transporters between the said side walls rotatable on vertical axes and having spirally arranged members for receiving and lowering bottles, vertically spaced shelves on opposite sides of said transporters having outer ends hingedly connected to said side walls and inclining downwardly therefrom with inner ends adjacent said transporters, doors hinged to the inner ends of said shelves, vertically disposed members adjacent inner ends of said shelves, means on said shelves engaging means provided on said members to limit swinging movements of said shelves from lower to upper positions, and means on said doors engaging means provided on said members to prevent swinging of said doors relative to the shelves when the shelves are in lower position,

means urging said doors upwardly from lower position, whereby the door of one shelf is held in closed position relative to a shelf next below when

said one shelf is in lower position and arranged whereby said door is released for swinging movements when said one shelf moves to upper position.

3. Apparatus for dispensing bottles and the like comprising in combination, a casing having side walls, transporters between the said side walls rotatable on vertical axes and having spirally arranged members for receiving and lowering bottles, vertically spaced shelves on opposite sides of said transporters having outer ends hingedly connected to said side walls and inclining downwardly therefrom with inner ends adjacent said transporters, doors hinged to the inner ends of said shelves, vertically disposed members adjacent inner ends of said shelves, means on said shelves engaging means provided on said vertically disposed members to limit swinging movements of said shelves from lower to upper positions, and means on said doors engaging means provided on said vertically disposed members to prevent swinging of said doors relative to the

shelves when the shelves are in lower position, means urging said doors upwardly from lower position, whereby the door of one shelf is held in closed position relative to a shelf next below when said one shelf is in lower position and arranged whereby said door is released for swinging movements when said one shelf moves to upper position, and means to rotate said transporters simultaneously.
